[57] CLAIM

The ornamental design for a hanger for a diver's wet suit, as shown and described.

DESCRIPTION

FIG. 1 is a side elevation view of a hanger for a diver's wet suit, showing my new design, both sides being similar;

FIG. 2 is an end elevational view thereof, both ends being similar;

FIG. 3 is a top plan view thereof; and

FIG. 4 is a bottom plan view thereof.
